UNITED STATES PATENT OFFICE.

WILLIAM BARBOUR, OF GLASGOW, SCOTLAND.

CORE FOR RESILIENT OBJECTS.

1,031,671.

Specification of Letters Patent. Patented July 2, 1912.

Application filed July 15, 1911. Serial No. 638,652.

To all whom it may concern:

Be it known that I, WILLIAM BARBOUR, M. B., C. M., Glasgow, a subject of the King of Great Britain and Ireland, and a resident of Partickhill, in the city and county of Glasgow, Scotland, have invented a certain new and useful Core for Resilient Objects, and of which the following is the specification.

10 The invention has for its object to provide a body formed of a combination of materials and having great resilience and thus suitable for use in the manufacture of golf-balls or their cores and in the manufacture 15 of cores for tires, of pads, of buffers, and of other objects in which great resilience is required.

The body consists essentially of two integers:—an inner member or core formed 20 from the depilated hides of animals in a moist condition, with or without previous treatment by washing for cleansing purposes or by boiling in water or a dilute alkali or acid such for example as caustic 25 soda or hydrochloric acid to increase resiliency, and an outer envelop of waterproof material, such as rubber, gutta-percha, or the like adapted to prevent drying of the inner member. The inner member may 30 either be held in tension being wound under tension upon itself or a nucleus after the manner of a golf-ball core, or may be held in compression by the envelop which may be applied in the form of tensionally 35 wound strips or tapes or under pressure in a mold.

Four examples of the carrying out of the invention are illustrated in section diagrammatically and to varying scales on an accompanying sheet of drawings.

In Figure 1 is illustrated a body in the form of a golf ball and comprising the two essential elements of the invention—a core A formed from the depilated hides of animals in a moist condition and an outer member or cover B of gutta-percha or like waterproof material serving to keep that core in its necessary moist condition and serving also as the usual outer cover of the ball. 45 The core is preferably in compression as far as may be possible, but to obtain a greater degree of compression than is possible in this manner there may be applied as shown in Fig. 2 to the core A before it is inclosed 50 in the outer member or cover B a tensional winding C of tape or the like.

In Fig. 3 is shown a tire formed from the combined materials. It comprises a core A of circular section of the hide in a moist condition, a binder or wrapping C of canvas, tape, or the like, here shown in two thicknesses, and an outer member B of rubber forming the tire tread and beads and also maintaining the hide core A in a moist condition.

In Fig. 4 is shown a similarly formed elastic and resilient plug or block for use as a buffer or the like. This comprises the core A, a binding wrapping C thereupon and a cover or outer member B of waterproof material. In each of these examples the core A may or may not be initially wound under tension.

It is clear that the invention lies not in the form of the article produced but jointly in the combination of materials composing it and in the maintained moist condition of the inner member, and it is to be understood that the examples illustrated are in no wise limitative of the application of the invention or the purposes for which it may be used.

I am well aware that straps of hide or skin have been wound while damp into cores for golf balls, but so far as I am aware, such cores have been intentionally permitted to become substantially dry before covering, whereby the advantage which I obtain is entirely lost.

What I claim is:—

1. An elastic and resilient body comprising an inner member formed from the depilated hides of animals in a moist condition and an outer member inclosing said inner member and of a waterproof material conserving the moistness of the inner member.

2. An elastic and resilient body comprising an inner member formed from the depilated hides of animals in a moist condition and wound under tension and an outer member inclosing said inner member and of a waterproof material conserving the moistness of the inner member.

3. An elastic and resilient body comprising an inner member formed from the depilated hides of animals in a moist condition, a compressing winding of flexible material thereupon and an outer member inclosing both and of a waterproof material conserving the moistness of the inner member.

4. An elastic and resilient body comprising an inner member formed from the dep-

lated hides of animals in a moist condition and wound under tension, a compressive winding of flexible material thereupon and an outer member inclosing both and of a 5 waterproof material conserving the moistness of the inner member.

In testimony whereof I have signed my

name to this specification, in the presence of two subscribing witnesses.

WILLIAM BARBOUR.
